UNITED STATES PATENT OFFICE

2,669,058

BOOKREST

Herbert J. Fadeley, Jr., Philadelphia, Pa.

Application June 15, 1951, Serial No. 231,815

5 Claims. (Cl. 45—58)

1

This invention relates to new and useful improvements in book rests and the primary object of the present invention is to provide a device for supporting a text book while being used where the reader occupies an arm-chair, permitting the reader to use the arm of the chair for writing while the book is supported at the extreme end of said arm.

Another important object of the present invention is to provide a book rest that is adaptable for use not only in conjunction with an arm-chair, but also on a desk or table, and as a support for one or more books while being carried from one classroom to another.

Another object of the present invention is to provide a book rest including a novel attaching member that is so constructed and arranged as to effectively grip the arm of a chair.

A still further aim of the present invention is to provide a book rest that is neat and attractive in appearance, strong and reliable in use, small and compact in structure, one that may be quickly and readily attached to or removed from a classroom arm-chair in a convenient manner, inexpensive to manufacture, and otherwise well adapted for the purposes for which the same is intended.

Other objects and advantages reside in the details of construction and operation as more fully hereinafter described and claimed, references being had to the accompanying drawings forming part hereof, wherein like numerals refer to like parts throughout, and in which:

Figure 1 is a fragmentary part view of a desk-chair and showing the present invention applied to the arm of the chair;

Figure 2 is a side view of Figure 1 and with a book supported by the present invention;

Figure 3 is a view similar to Figure 1 but showing the invention inverted and the arm of the chair with a center board or brace;

Figure 4 is a side view of the invention resting upon a desk or table;

Figure 5 is a sectional view of the present invention to show the manner in which the ledge-forming strips are secured to the flat support; and,

Figure 6 is a fragmentary perspective view of the attaching member forming part of the present invention.

Referring now to the drawings in detail, wherein for the purpose of illustration, there is disclosed a preferred embodiment of the present invention, the numeral 10 represents an elongated and flat, substantially rectangular, sup-

2

port to whose end edges are secured first and second substantially rectangular ledge-forming strips 12 and 14.

The ends of the strips 12 and 14 project laterally from the support 10 and the strips 12 and 14 are spaced parallel to each other but perpendicular to the support 10. The side edge of the strip 12 that is secured to the support 10 is flush with one face of the support 10 and the side edge of the strip 14 that is secured to the support 10 is flush with the other face of the support 10.

Apertures 16 and 18 are provided in the ends of the strip 12 and apertures 20 and 22 are provided in the ends of the strip 14. The apertures 16, 18, 20 and 22 are inclined relative to the longitudinal axis of the support 10, the apertures 16 and 20 are aligned with each other, and the apertures 18 and 22 are also aligned with each other.

Means is provided for removably securing the support 10 and strips 12, 14 to a supporting structure. This means comprises a U-shaped wire member 24 including a pair of leg portions 26 and 28, and a web portion 30. The outer ends of the leg portions 26 and 28 are bent inwardly toward each other and parallel to the web portion 30 to form lugs or arms 32 and 34.

The leg portion 26 is slidably received in the apertures 16 and 20 whereas the leg portion 28 is slidably received in the apertures 18 and 22. The arms 32 and 34 overlie the ledge-forming strip 12 whereas the web portion 30 underlies the ledge-forming strip 14. The apertures 16, 18, 20 and 22 are so positioned as to locate the parts of the leg portions 26 and 28, between the strips 12 and 14, between planes flush with the side faces of the support 10 so that a book B may rest against the support 10 without engaging the member 24. The book will engage the member 24 at the juncture of 24 with apertures 20 and 22 or 16 and 18 on the face side of strips 12 and 14, as the case may be.

The face of the strip 14 closest to the support 10 is formed with a plurality of spaced parallel longitudinal grooves 36 one of which is located at the juncture of said support with the strip 14 to accommodate the leaves of a book B. The face of the strip 12 closest to the support 10 is also formed with a plurality of spaced parallel grooves with the support 10 to accommodate the leaves of the book B.

In practical use of the present invention with the arm A of a desk-chair having a brace or center board C, as shown in Figure 3, the se-

cured edge of the strip 12 rests against the upper surface of the arm A and the lugs 32 and 34 engage under the arm A. The support 10 is retained in a vertically inclined position since the same is overbalanced at its upper end to force the lugs 32 and 34 against the undersurface of the arm A.

When the book rest is used with arms A' of desk-chairs having no center beam, the secured edge of the strip 14 rests upon the arm A' and the web portion 30 bears upwardly against the undersurface of the arm A' to retain the support 10 vertically inclined as shown in Figures 1 and 2.

The present book rest may also be supported upon a flat horizontal surface S such as a desk or table top with the inner secured edge of the strip 12 and the outer unsecured edge of the strip 14 resting upon the surface S as shown in Figure 4.

In view of the foregoing description taken in conjunction with the accompanying drawings, it is believed that a clear understanding of the device will be quite apparent to those skilled in this art. A more detail description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. A book rest comprising an elongated support member, first and second ledge-forming strips secured to and projecting laterally from the ends of said support member and from opposite sides of the support member, each of said strips having an end aperture, and a U-shaped wire attaching member having leg portions slidable in said apertures and a web portion underlying one of the strips, and lateral projections on said leg portions overlying the other strip.

2. A book rest comprising an elongated and flat support, first and second ledge-forming strips secured to the ends of said support and paralleling each other, said first strip extending from one face of the support and said second strip ex-

tending from the other face of the support, each of said strips having an end aperture, and a U-shaped wire attaching member having leg portions slidable received in said apertures and a web portion underlying one of said strips, the outer ends of said leg portions being bent to form perpendicular portions overlying the other strip, the parts of said leg portions being said strips lying between planes flush with the side faces of said support.

3. The combination of claim 2 wherein each of said strips includes a face having parallel grooves therein.

4. The combination of claim 3 wherein at least one of said grooves is located at the juncture of said support with one of said strips.

5. A book rest comprising an elongated flat panel having upper and lower end edges and forward and rear faces, upper and lower strips secured to the upper and lower edges of the panel, said lower strip projecting rearwardly from the rear face of the panel and said upper strip projecting forwardly from the forward face of said panel, said strips having end apertures, a U-shaped wire attaching member having leg portions slidable received in said end apertures and a web portion underlying the lower strip, and said leg portions having perpendicular free end portions remote from said web and overlying said upper strip.

HERBERT J. FADELEY, JR.
